GRINDING MACHINE

Leonard E. Ross, Dallas, Tex.

Application October 22, 1934, Serial No. 749,380

5 Claims. (Cl. 51—135)

This invention relates generally to grinding machines, and more particularly, to a certain new and useful improvement in surface grinders of the abrasive belt type.

5 My invention has for its prime object the provision of a grinding machine especially, though not exclusively, adapted for finishing or grinding fillets and concave and irregular surfaces in general.

10 My invention has for another object the provision of a grinding machine of the type stated, in which the working surface of the belt is cushioned or resiliently supported, so that the belt may readily flex or yield to suit the contour of the work while elastically resisting such flexure sufficiently for efficiently performing its intended grinding functions.

15 My invention has for still another object the provision of a grinding machine of the type mentioned in which one of its belt-supporting pulleys is readily adjustable, so as to train the belt to the desired usable position thereof on the pulley, that is to say, either toward the center or toward a side margin of the pulley, such result being obtainable without the interposition of belt guides or other members engaging the side margins of the belt.

20 My invention has for a further object the provision, in a grinding machine of the abrasive-belt type, of a pulley support for the grinding belt provided with an elastic rim yieldable to grinding pressure over its entire face and especially flexible at its side circumferential margins for yielding to the working of concave objects at the side margins of the belt.

25 My invention has for a still further object the provision of a portable or bench type of abrasive-belt grinding machine which is simple and compact in structure and inexpensive to manufacture and maintain in usable condition, and to improve the construction of abrasive-belt grinders in general.

30 And with the above and other objects in view, my invention resides in the novel form, construction, arrangement, and combination of parts presently described and pointed out in the claims.

35 In the accompanying drawings (two sheets).—

40 Figure 1 is a top plan view of an abrasive-belt type of grinding machine embodying my invention;

45 Figure 2 is a similar view showing the motor shifted longitudinally on the base for tensioning the abrasive-belt;

50 Figure 3 is a side elevational view of the machine;

55 Figure 4 is a fragmentary sectional view taken approximately along the line 4—4, Figure 2;

60 Figure 5 is a fragmentary sectional view taken approximately along the line 5—5, Figure 3, a shifted position of the belt being shown by dot-dash lines; and

65 Figure 6 is a view similar to Figure 5, showing the belt in use, the work being shown in dot-dash lines.

70 Referring now more in detail and by reference to the drawings, which illustrate a preferred embodiment of the invention, the machine includes a suitably elongated substantially rectangular hollow base 1, which at its rear end and on its upper surface supports a pair of transversely spaced longitudinal rails or slide-ways 2.

75 Slidably mounted on the rails 2 for reciprocation, is a carriage 3, which supports, in turn, a suitable prime-mover, such as an electric-motor 4, provided on its main-shaft with a suitably dimensioned pulley 5 for purposes presently appearing.

80 Depending from the carriage 3 in and through a suitable longitudinal slot provided for the purpose in the upper wall of the base 1, is a lug 6 having a pivot-connection at its lower end with one end of a link 7, which, in turn, extends forwardly within the confines of the base 1, and at its other end is pivotally connected with a hand-lever 8 at a point intermediate the ends thereof. The lever 8 also, in turn, is pivoted at one end, as at 9, to the base 1 and at its free end projects outwardly through a slot 10 provided in a side wall of the base 1, the latter being arcuately contoured or rounded away suitably for the purpose, as best seen in Figures 1 and 2.

85 Attached to and upon the inner face of the side wall of the base adjacent the slot 10, is a ratchet-bar or serrated member 11, whose teeth 12 are adapted for engagement by a detent 13 depending in suitable position from the hand-lever 8, as best seen in Figure 4, for retaining the lever 8 in rearwardly swung position for adjusting the position of the carriage 3 on the rails 2, for purposes shortly appearing.

90 At its forward end, and at the corner thereof substantially opposite to the location of the lever 8, the base 1 is provided with a lateral projection or bracket 14 carrying an upstanding pivot pin 15, on which is pivotally or swivelly mounted a pulley-stand 16, extending inwardly from which is an arm 17 having a slot-and-pin engagement, as at 18, with a nut 19 working on an elongated screw or actuating shaft 20 journaled in and between a pair of longitudinally spaced bearings 21.

suitably upstanding from the upper surface of the base 1.

At its forward end, the screw 20 projects suitably beyond the forward bearing 21 and is equipped with a hand-wheel 22 for manual manipulation, with ensuing traverse of the nut 19 on the screw 20, whereby, as desired, the stand 16 may be rotatably shifted on its pivot 15, with consequences presently to be described.

10 Extending obliquely upwardly and forwardly from the base of the stand 16, is a standard 23, which at its upper free end supports an inwardly extending lateral stub-shaft 24 carrying a suitable bearing 25, preferably of the annular ball-bearing type, for rotatably supporting a belt-supporting pulley 26, as best seen in Figures 1, 2, and 3.

The pulley 26, which is of rigid construction and preferably is made of aluminum or other light weight metallic material, is provided with a relatively wide rim 27, which is circumferentially embraced by an annular cushion facing or lagging 28 composed of a suitable resilient or elastic material, preferably rubber or the like.

25 On the underside of its lateral or side margins, the cushion rim-facing 28 is beveled or undercut, as at 29 in Figure 5, for thus progressively diminishing the resistance, or weakening the strength, of the cushion toward its side margins, whereby the cushion 28 is at such point more especially flexible or yieldably responsive to radial pressure applied on the pulley during the working of the machine, as will presently be more particularly pointed out.

30 On and between the driving and driven pulleys 5 and 26, respectively, is trained an abrasive-belt 30 comprising a cloth or other flexible belting material carrying a surface coating of abrasive substance, in the usual manner well known in the art.

40 Current for motivating the motor 4 may be supplied from any convenient source, the machine in the present instance being equipped with an extension cord or cable 31 attached to and leading suitably into the base 1 and provided at its free end with a plug 32 for engaging a wall-socket or the like, not shown.

In the conventional manner, a manually operable snap switch 33 is mounted on the base 1 and connected in the circuit of the motor 4 for controlling the actuation thereof at the will of the operator.

55 In use and operation, the resilient rim-facing or cushion 28 is employed as the support for the surface of the grinding belt 30 where the grinding operation is to be done. When an article is to be ground, it is simply pressed against the rapidly moving surface of the abrasive-belt as it passes over the pulley 26.

When, as in the use for which my grinder is 60 particularly adapted, the surface to be ground is of irregular shape, it will be readily understood that the elastic cushion 28 which supports the belt 30 will yield to the contour of the work, thus enabling the polishing or grinding of such surfaces in a simple and facile manner.

More particularly, when the surface to be ground includes a concave surface, such as a fillet or the like, the work is engaged with a marginal side of the belt 30. As has been said, the 70 cushion 28 has a progressively increasing degree of flexibility toward its side margins due to the undercutting 29, and hence, when the work is applied to the belt for engaging the fillet with the marginal side thereof, the cushion 28 yields 75 to conform the surface of the belt 30 with the

shape of the fillet, as clearly shown in Figure 6, the work being therein indicated by the dot-dash lines.

It will be readily apparent that, in such fillet grinding work, the side margins of the belt 30 5 become more or less rapidly worn and ultimately useless for their intended purpose. In such event, the screw 20 is manipulated for rotating the stand 16 on its pivot 15, which, in turn, shifts the pulley 26 laterally in an arcuate path to one side or the other of its normal position. The pulley 26 then also has a slight angular displacement with respect to the driving pulley 5, whereby the belt 30 is caused to shift laterally on the pulley 26 until the worn margin of the belt projects over and 15 to one side of the cushion-rim 28, as shown by dot-dash lines in Figure 5.

It is then a simple matter to cut off the worn margin of the belt 30 and to train the belt over the pulley until the newly trimmed side margin 20 of the belt is flush with the corresponding margin of the cushion 28, as shown by the full lines in Figure 5, the belt 30 being thus, in a highly expedient and facile manner, restored to its original effectiveness for fillet grinding purposes. 25

The hand-lever 8, in co-operation with the rack 11, is employed for shifting the motor 4 and pulley 5 longitudinally in the plane of the belt and rearwardly on the base 1 for tensioning the belt 30 between the pulleys 5 and 26, the co-operation of 30 the detent 13 with the teeth 12 of the rack 11 serving to retain the pulley 5 in adjusted position against the tension of the belt.

However, the hand-lever 8 may also be most usefully employed for applying an extra tension 35 on the belt 30 for causing the same to hug the cushion 28 with sufficient force to flex or bend the side margins of the belt 30 over the undercut margins of the cushion 28, so that the side margins of the belt 30 partake of a curvilinear 40 shape highly suitable for fillet grinding purposes, as best seen in Figure 2.

In such manner, the pressure applied on the work, for conforming the belt to the fillet contour, may be considerably reduced, with consequent reduction in the wear and prolongation of the life of the belt. 45

The machine may be readily manufactured, is sturdy and durable, and efficient in the performance of its intended functions. 50

And it is to be understood that changes and modifications in the form, construction, arrangement, and combination of the several parts of the machine may be made and substituted for those herein shown and described without departing from the nature and principle of my invention. 55

Having thus described my invention, what I claim and desire to secure by Letters Patent is,—

1. A grinding machine including an abrasive belt, and a pulley for supporting the working portion of the belt, said pulley comprising a rigid center provided with an elastic covering on its rim, and the covering at its lateral margins being undercut providing a groove between the outer surface of the covering and the rim of the center. 60

2. In a grinding machine, an abrasive belt, and means including spaced pulleys for supporting the belt for movement, one of said pulleys comprising a rim and a cushion-lagging embracing the rim, said lagging being structurally weakened in a side face for increasing its flexibility at its margin, whereby the lagging is marginally yieldingly conformable to the con- 75

tour of work presented for grinding upon the belt at said pulley.

3. In a grinding-machine, an abrasive belt, and means including spaced pulleys for supporting the belt for movement, one of said pulleys comprising a rim and a rubber lagging embracing the rim, said lagging being undercut in its opposite side faces for increasing its flexibility at its opposite margins, whereby the lagging is marginally elastically conformable to the contour of work presented for grinding upon the belt at said pulley.

4. In a grinding-machine, an abrasive belt, spaced pulleys for supporting the belt for move-

ment, means for tensioning the belt on the pulleys, and a resilient lagging on one of said pulleys marginally weakened for taking, on tensioning of the belt, a curvilinear shape relatively to said pulley.

5. In a grinding machine, an abrasive belt, spaced pulleys for supporting the belt for movement, means for tensioning the belt on the pulleys, and an elastic lagging on one of said pulleys having a recess in a side face for taking, on tensioning of the belt, a curvilinear shape relatively to said pulley.
